(57) **CLAIM**

The ornamental design for a canister cover, as shown and described.

DESCRIPTION

FIG. 1 is a perspective view of the invention.

FIG. 2 is a top view of the invention.

FIG. 3 is a front view of the invention.

FIG. 4 is a rear view of the invention; and,

FIG. 5 is a side view of the invention with the opposite side being a mirror image thereof.

The broken lines shown in the drawings are for illustrative purposes only and form no part of the claimed design.
